DESIGN FOR A CAUTERY UNIT

John A. Korengold, Chicago, Ill.

Application October 3, 1938, Serial No. 80,206

Term of patent 3½ years

To all whom it may concern:

Be it known that I, John A. Korengold, a citizen of the United States, residing at the city of Chicago, county of Cook, State of Illinois, have invented a new, original, and ornamental Design for a Cautery Unit, of which the following is a specification, reference being made to the accompanying drawing, forming a part thereof, in which in partially open position embodying my new design;

I claim:

The ornamental design for a cautery unit, substantially as shown and described.

JOHN A. KORENGOLD.
